UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

TRAIN CONTROL ACKNOWLEDGING CONTACTOR.

Application filed March 16, 1926. Serial No. 95,104.

This invention relates to automatic train control and more particularly concerns a contacting device for use in connection with train control systems employing the acknowledging principle.

In certain types of automatic train control systems, it is deemed advisable to employ means which will encourage the engineer to maintain a sharp lookout for wayside signals and to recognize their indications. This is ordinarily accomplished by the use of some type of manually operable acknowledging means, which, if operated before the train passes a signal displaying an unfavorable indication, acts to suppress or nullify a brake application, to substitute a low speed limit for an automatic stop, or in some other manner to relieve the engineer of some annoyance or delay which would otherwise have been imposed. Since the acknowledging device acts when operated to suppress certain automatic restrictions, it is evident that the engineer could readily avoid all such automatic restriction by holding, tying or otherwise maintaining the acknowledging device in its operated position, and the object of providing an automatic control system would be defeated. It has been therefore deemed necessary to provide means in connection with the acknowledging device for causing a further automatic restriction or other penalty if the device is maintained in its operated position for more than a predetermined time interval.

With the above and other considerations in mind, it is proposed in accordance with the present invention to provide an acknowledging contactor for automatic train control systems which acts to close certain contacts when operated, and which is provided with means for opening certain other contacts if the first mentioned contacts have been maintained closed for more than a predetermined time interval. It is further proposed to provide a device of this type which is compact and rugged in construction, and in which the operating mechanism is completely enclosed in a casing to prevent access thereto by unauthorized persons.

Other objects, advantages and characteristic features of the invention will be pointed out or will become apparent as the description thereof progresses.

In describing the invention in detail, ref-

erence will be made to the accompanying drawing, in which:

Fig. 1 represents a side view of the acknowledging contactor comprising the present invention, a portion of the casing cover having been broken away to show the mechanism;

Fig. 2 is a section taken along the line 2—2 of Fig. 1 and viewed in the direction of the arrows; and

Fig. 3 is a perspective view of the clock-work mechanism employed in the contactor of Fig. 1, certain of the parts being broken away and separated to show the interior construction.

Referring to the drawings, and more particularly to Fig. 1, the contactor mechanism of the present invention is enclosed within a casing 1 having a cover 2 hinged thereto by the adjustable eye bolts 3 and 4 which engage the projections 5 and 6 respectively on the casing 1. A gasket 7 is provided in a groove at the edge of the cover 2 to insure a weather proof closure, and the cover is secured in its closed position as shown by the nut 8 engaging an eye bolt 9 which is hinged to the casing by the pin 10 passing through the projecting lugs 11 on the upper surface thereof. The nut 8 bears against a slotted lug 12 on the cover 2, and is provided with a wing or extension 13 having an opening therein to permit the nut 8 to be locked or sealed to a suitable member 14 secured to the cover 2, thus locking or sealing the cover in its closed position.

The casing 1 is provided with two oppositely disposed openings in its lower side walls, for the reception of conduit fittings carrying wires leading to the mechanism within the casing, a conduit fitting 15 being shown secured in one of these openings, and a plug 16 being shown in the other. The back wall 17 of the casing 1 is provided with three suitably disposed openings 18 for permitting the device to be secured to a support.

A mechanism frame 19 is secured within the casing 1 by means of the screws 20 passing through openings in the frame and engaging the integral posts 21 on the back wall 17 of the casing. The frame 19 is of general inverted U shape and is channeled as shown in Fig. 1, a strip or block 22 of insulating material being secured between

the downwardly projecting legs of the frame 19 by the screw 23 as shown.

Any suitable number and arrangement of contacts may be used in connection with the device of the present invention, and as in most train control systems where an acknowledging device of this type is used it is necessary to close certain contacts immediately upon the operation of the device and 10 to open other contacts after the device has been maintained operated for a predetermined time interval, two normally opened contacts and one normally closed contact have been shown. Each set of contacts comprises two contact members which are 15 hingedly and resiliently mounted on the insulating block 22. Each contact member comprises a metallic base portion 24 having a terminal screw 25 secured thereto or integrally therewith and an upwardly extending integral portion 26 carrying a pin 27 having an enlarged head. A movable contact arm 28 is hinged to the base portion 24 as shown, and is provided with an enlarged opening 29 through which a pin 27 passes. A spring 30 is located on the pin 27, being compressed between the enlarged head thereof and the arm 28, thus biasing the arm 28 against the portion 26 of the base 24. One of the two 35 contact arms of each set of contacts is provided with a resilient metallic contact element 31, while the other arm carries an adjustable contact button 32 of refractory material such as carbon. In the arrangement shown, the set of contacts designated as A are biased to their closed position, and one of the contact arms of this set carries an upwardly projecting contact operating strip 33. The sets of contacts designated B 40 and C are normally biased to their open positions, and the right-hand arms of each of these sets are connected to move together by the bar 34 of insulating material which passes through an opening 35 in one of the 45 arms 28 of the set B as shown in Fig. 2. The right-hand arm of the set of contacts designated as C carries an upwardly projecting operating strip 36 as shown in Fig. 1. The terminal screws 25 on the base portions 50 24 of the contact members pass through openings in the insulating block 22 as shown, and are provided with nuts 37 for securely clamping the base portions in place and for making the necessary electrical connections. 55 The mechanism frame 19 carries two integrally formed upwardly projecting parallel bearing supports 38 and 39 which are slightly offset from the sides of the frame 19 as shown in Fig. 2. The supports 38 60 and 39 are provided with aligned openings in which are secured the bronze or brass bushings 40 and 41 respectively, suitable washers 42 being preferably inserted between the support 38 and the cover 2 as 65 shown. A shaft 43 is journaled in the bush-

ings 40 and 41 and passes through an opening 44 in the cover 2, an operating handle 45 being secured to the square end 46 of the shaft 43 by the nut 47 which engages the screw threaded end 48 of the shaft and is 70 locked in place by the pin 49.

A contact operating crank member D is secured to the shaft 43 between the supports 38 and 39. This crank D comprises a bifurcated member having two sleeve-like 75 portions 50 and 51 connected by an angularly disposed yoke 52, and two downwardly extending crank arms 53 and 54 provided with aligned openings in their lower ends. The sleeve-like portions 50 and 51 are provided with aligned openings through which the shaft 43 is passed, and are secured to turn with the shaft by the pins 55 or other suitable means. A pin 56 passes through the aligned openings in the crank arms 53 80 and 54, and connects these arms to the enlarged head 57 of a contact operating rod 58, the opposite end of which rod is slidably supported in an opening in the integral downwardly projecting web 59 of the mechanism frame 19. A downwardly projecting arm 60 is pinned or otherwise rigidly secured to the end of the rod 58 which projects through the web 59, the lower end of this arm 60 being provided with a contact operating member 61 of insulating material which is positioned to engage the strip 36 when the rod 58 is moved to the left. A spring 62, compressed to an initial tension, is located on the rod 58 between the enlarged head 57 thereof and the web 59, this spring 62 serving to bias the rod 58 together with the contact operating member 61, the crank member D, the shaft 43 and the operating handle 45 to their normal positions as 100 shown.

From the description of the apparatus given thus far, it will be apparent that a movement of the operating handle 45 to the right, or in a clock-wise direction, causes 110 the rod 58 to move to the left against the pressure exerted by the spring 62, the insulating member 61 on the arm 60 engaging the contact operating strip 36 and closing the contacts designated B and C. In order to 115 limit the extent to which the normally opened contacts B and C may be compressed by the movement of the rod 58, a stop comprising an adjustable set screw 63 is provided in the frame 19, and arranged to be 120 engaged by the free end of the rod 58 in its extreme operated position.

Considering now the operating mechanism for the normally closed contacts A, a clock-work operated crank member E is journaled 125 to turn freely on the shaft 43 between the sleeve-like portions 50 and 51, of the operating crank member D. The crank member E comprises a downwardly extending integral arm 64 provided with a tip 65 of insulating 130

material, an angularly disposed extension 66 carrying a stop screw 67, and an integral gear sector 68. The extension 66 is disposed to lie adjacent the yoke 52 of the operating crank D with the stop screw 67 in engagement with said yoke when the device is in its normal position as shown. The sector 68 is provided with gear teeth engaging a driving gear 69 of a retarded clockwork mechanism which acts to bias the crank member E to turn in a clockwise direction. The arm 64 is arranged to engage the contact operating strip 33 of the contacts A and to open these contacts when the crank 15 E is moved to the extreme clockwise position.

The retarded clockwork mechanism, designated as a whole as K and shown in detail in Fig. 3, comprises two rectangular parallel side plates 70 rigidly connected together by the screws 71 and secured to the lugs 72 on the frame 19 by means of the screws 73. A plurality of shafts 74, 75, 76, 77 and 78 are journaled in the side plates 70 and carry a train of reduction gears. Secured to the shaft 74 are a driving gear 69 engaging the sector 68, a flat coil spring 79 secured between the shaft 74 and one of the screws 71, and arranged to bias this shaft to turn in a counter clockwise direction, and a gear 80. The gear 80 engages a pinion 81 secured to the shaft 75, a ratchet wheel 82 is also secured to the shaft 75 and is engaged by a spring pressed pawl 83, carried by a gear 84 which is free to turn on the shaft 75, the gear 35 84 is connected through the reduction gearing comprising a pinion 85, the gear 86, and the pinion 87 to an escapement wheel 88, the rotation of which is retarded in the well known manner by a pallet 89 having a pendulum 90 and carried on the shaft 78. It is evident that the clockwork mechanism operates to move the sector 68 in a counter clockwise direction, the motion of the various parts being retarded by the escapement 40 45 wheel 88 and the pallet 89, acting through the gear train, the direction of movement of the various gears in moving the sector 68 being indicated by the arrows. When the sector 68 is moved in a counter clockwise direction, the shaft 74 is turned in a clockwise direction to rewind the spring 79, the ratchet wheel 82 being moved in a counter clockwise direction past the pawl 83, and the remaining reduction gears, escapement wheel 88 and 50 55 pallet 89 remaining stationary during this rewinding process.

The arrangement of the mechanism is such that the spring 62 on the rod 58 is strong enough to rewind the spring 79 of the clockwork mechanism, these springs being connected through the rod 58, the operating crank D, the crank member E and the sector 68.

In operation, when the engineer wishes to 60 65 close the contacts B and C in acknowledging

wayside signal indications or other conditions, he moves the operating handle 45 to the right, turning the shaft 43 in a clockwise direction, compressing the spring 62 and closing the contacts B and C. As the 70 operating crank member D is moved in a clockwise direction, the yoke 52 thereof disengages the stop screw 67 on the extension 66 of the crank member E, thus permitting the retarded clockwork mechanism K to 75 move the crank member E, through the sector 68, in a clockwise direction, and moving the arm 64 to the left toward the contact operating strip 33. In the normal operation of the device, this motion of the clockwork 80 operated crank member E is slow enough so that the contacts B and C may be maintained closed for a time interval sufficient for acknowledging purposes before the arm 64 engages the contact operating strip 33. After 85 the proper interval of acknowledgement, the engineer releases the operating handle 45 which is returned to its normal position by the spring 62, acting through the crank member D, the yoke 52 of the member D engaging the stop screw 67 of the member E and moving the member E in a counter clockwise direction until the head of the arm 60 on the rod 58 engages the web 59 of the frame 19. The return movement of the 95 crank member E rewinds the spring 79 through the sector 68 and the driving gear 69 as described above.

If the engineer attempts to avoid an automatic restriction by tying, holding or otherwise maintaining the handle 45 in its operated or clockwise position, the clockwork mechanism K, acting through the crank member E for a predetermined time interval, moves the arm 64 to a position to open 100 the contacts A, which are preferably included in a so-called penalty circuit, and suitable controls are operated upon the opening of these contacts to automatically restrict the progress of the vehicle or otherwise to penalize 105 the engineer.

The time interval which elapses between the operation of the handle 45 and the opening of the contacts 33 may be conveniently 110 adjusted or regulated by means of the stop screw 67 which governs the initial position of the crank member E. If the screw 67 is turned to move the member E in a counter clockwise direction, the time interval is increased, and if the screw is backed off to 115 permit the member E to move in a clockwise direction, the time interval is decreased.

It is evident from the description given that a simple and compact mechanism has been devised for accomplishing the well 120 125 known acknowledging operation in train control systems. It should be particularly noted that the mechanism is entirely enclosed and may be locked or sealed to prevent access thereto by unauthorized persons and to house 130

and protect the operating mechanism and the wiring connections. The device is conveniently constructed in compact form and can be mounted at any desired point in the locomotive cab. If desired, the casing 1 and the shaft 43 may be slightly altered to permit the attachment of the operating handle 45 on the opposite side of the casing from that shown in the drawings. It should be observed that the time element mechanism is automatic, that is, it need not be manually re-wound or returned to its initial position after operation.

Although the acknowledging contractor of the present invention has been described in a rather specific manner and in connection with a single specific embodiment, it should be understood that various changes and modifications in the design and construction of the device may be made without departing from the scope of the invention as defined by the appended claims.

What it is desired to secure by Letters Patent is:—

1. An acknowledging contactor for automatic train control systems comprising a shaft, manual operating means for said shaft, operated means rigidly secured to said shaft for moving certain electrical contacts when said shaft is moved in one direction to its operated position, and power operated means carried by, and rotatable relatively to, said shaft for operating certain other electrical contacts if said shaft is maintained in its operated position for more than a predetermined time interval.

2. An acknowledging contactor for automatic train control systems comprising a pair of normally open contacts, a shaft, manually operable means fast on said shaft for closing said contacts when moved from its normal position to its operated position, a pair of normally closed contacts, clock-work means, including a member loose on said shaft, released by said manually operable means when moved from its normal position and acting to open said normally closed contacts if said manually operable means is maintained in its operated position for more than a predetermined time interval, and spring means for returning said manually operable means to its normal position, said spring means also acting to rewind said clock work means while returning said manually operable means to its normal position.

3. An acknowledging contactor for automatic train control systems comprising manually operable means, acting when moved from the normal to the operated position to close certain contacts, power operated means released by said manually operable means when moved from said normal position and acting to open other electrical contacts if said manually operable means is

maintained operated for more than a predetermined time interval, and adjustable means for adjusting the relative positions of said manually operable means and said power operated means when said manually operable means is in its normal position whereby said time interval may be adjusted.

4. An acknowledging contactor for automatic train control systems comprising a shaft, a handle and a fixed crank on said shaft, a slidably mounted rod connected to said fixed crank and acting to close normally open contacts when said handle is moved to its operated position, spring means carried by said rod for returning said rod, said fixed crank and said handle to their normal positions, a crank movably mounted on said shaft, clock-work mechanism engaging said movable crank and acting to move said movable crank from its normal to its operated position in a predetermined time interval when said movable crank is released, normally closed contacts opened by said movable crank when in its operated position, and means on said fixed crank for engaging said movable crank for moving said movable crank to and maintaining it in its normal position when said fixed crank is moved to and maintained in its normal position.

5. An acknowledging contactor for automatic train control systems comprising a shaft, an operating handle and a fixed crank secured to said shaft, said fixed crank comprising two downwardly extending legs connected by a yoke, a rod connected to said downwardly extending legs of said fixed crank and acting to close normally open contacts when said shaft is moved to its operated position, spring means carried by said rod and biasing said shaft to its normal position, adjustable stop means for limiting the movement of said shaft, a movable crank on said shaft between the downwardly extending legs of said fixed crank, adjustable means on said movable crank engaging said yoke whereby said movable crank is maintained in its normal position by said fixed crank, and clock work means engaging said movable crank and acting to move said movable crank from its normal position to its operated position in a predetermined time interval when released by the movement of said yoke out of engagement with said adjustable means on said movable crank, said movable crank acting to open the normally closed contacts when in its operated position, said spring means acting to rewind said clock work mechanism when said shaft is returned to its normal position.

6. In an acknowledging contactor for automatic train control systems, a casing, a removable cover on said casing, means for maintaining said cover closed, a shaft passing through an opening in said cover, means within the casing rigidly secured to the shaft

for operating certain electrical contacts when said shaft is moved in one direction to its operated position, power operated means within the casing, movably carried by said shaft, for operating certain other electrical contacts if said shaft is maintained in its operated position for more than a predetermined time interval, and an operating handle secured to said shaft and extending 10 outside of said casing.

7. An acknowledging contactor for automatic train control systems comprising manually operable means, acting when moved

from the normal to the operated position to operate certain contacts, power operated means released by said manually operable means when moved from the normal position and acting to operate other electrical contacts if said manually operable means is maintained operated for more than a predetermined time interval, and means for adjusting the relative positions of said manually operable means and said power operated means.

In testimony whereof I affix my signature.

CHARLES S. BUSHNELL.
